UNITED STATES PATENT OFFICE.

GEORGE H. CHANDLER, OF LOWELL, MASSACHUSETTS.

MECHANISM FOR STRIPPING THE FLATS OF CARDING-MACHINES.

SPECIFICATION forming part of Letters Patent No. 244,546, dated July 19, 1881.

Application filed September 17, 1880. (No model.)

To all whom it may concern:

Be it known that I, GEORGE H. CHANDLER, of Lowell, in the county of Middlesex and State of Massachusetts, have invented an Improvement in the Mechanism for Stripping the Flats of Carding-Machines, of which the following is a specification.

The object of my invention is to provide a mechanism which can be applied to the card-stripping mechanism known as the "Wellman stripper," to automatically drive it, during the act of raising and stripping the flats of a carding-machine, at a different and greater rate of speed than it is driven while traveling from one flat to another, and at the same time to effect such change in the speed of the machinery without jarring or straining any part of it.

My present device is an improvement upon the mechanism described in Patent No. 222,812, issued to me December 23, 1879.

I attain the object of my invention by the mechanism illustrated in the accompanying drawings, in which—

Figure 1 is an end elevation of a portion of a carding-machine, showing the stripping mechanism with my improvements applied thereto. Fig. 2 is a side elevation of the same. Fig. 3 is a view of the end of the card-cylinder shaft with the fast and slow speed pulleys and their connecting train, part of one of the pulleys being broken away to show the train. Fig. 4 is a section of the same on line A A, Fig. 3. Fig. 5 is a section of the mechanism shown in Fig. 3 on line B B of said figure. Fig. 6 is an enlarged view of the wheels c and k seen in Fig. 3. Fig. 7 is a sectional view of the same. Fig. 8 is a sectional view of pulley D upon line B B of Fig. 3. Fig. 9 is a sectional view of pulley E upon line B B of Fig. 3, showing the internal teeth therein. Fig. 10 is a section of the case F through the center on a plane parallel with the studs on which the wheels of the train are rotated, showing them in elevation and the train in section.

45 a is the main cylinder-shaft.

P P are the top-flats of the machine.

Q is one of the arms to which the stripper is attached.

M is the cam-wheel which operates the stripper and raises the flats P P. These several

parts are operated and the whole mechanism travels back and forth on the circle O in the usual manner, the cam M being driven by a pulley, H, and train h, R, and r, the pulley H being driven by a belt, L, which receives motion from a pulley driven by the shaft a. 55

D is a pulley fast upon the card-cylinder shaft a, having attached to or formed upon its hub d the gear-wheel s, which projects beyond the hub d and engages with gear-wheel e, hereinafter to be described. 60

E is a pulley, adapted to turn freely upon the hub d, and having teeth cut upon the inner surface of its rim, making it an internally-toothed wheel, into which teeth teeth of the 65 pinion k upon the ratchet-hub k', hereinafter described, engage.

F is a plate or disk having a rim, which forms a case of substantially the diameter of the pulleys D and E, and is attached to the frame G, 70 which carries the stripping mechanism, or it may be attached to any adjacent part of the machine which will prevent its rotation. Upon the plate or disk F is the stud h, upon which is placed the toothed wheel e, which engages with the toothed wheel s and pinion j, rigidly secured to the said wheel e. There is also upon the plate or disk a stud, g, upon which is placed the pinion k, which has upon it a ratchet-hub, k', upon which the wheel c, which 75 engages with the pinion j, is free to move in one direction, but is prevented by the pawl y from turning in the other, and the pinion k will, when the wheel c is revolved in one direction, be driven with it, but can at any time 80 revolve at a greater speed in the same direction if any force be applied directly to its periphery independent of the wheel c. The pawl y is placed in a cavity cut in the wheel c, and drops into the notch cut in the ratchet-hub k', being held in place in the said notch, or into contact with the ratchet-hub k', when not in the notch, by a spring, x, placed in a channel 85 cut in the wheel c, these parts being covered by a washer, z, to exclude dirt or other foreign substances. 90

When these described parts are put in operative position the pulleys D and E have their rims abutting against one another loosely, and the wheel s, moving with the shaft a, 100

drives the wheel *e*, to which is attached the pinion *j* which drives the wheel *c*, which, through the pawl *y* and ratchet-hub *k'*, drives the pinion *k*, which, engaging in the internal 5 teeth of the pulley *E*, drives it in the same direction as the pulley *D*, but at a much slower speed.

By reason of the freedom of movement permitted to the pinion *k*, as above described, the 10 pulley *E* may be rotated at the same speed as the pulley *D* if from contact with any object touching both at the same time the power of the faster is transmitted to the slower, so that a belt being shipped from one to the other, instead of slipping and wearing upon the one or the other, as one has a greater hold than the other, will drive both pulleys at the speed of the faster until it is entirely upon one pulley, after which it will move at the normal surface 15 speed of that pulley.

J is a slotted cam attached to the cam *M* and moving with it.

K is a belt-shipper operated by the cam *J*, having its forked end swinging very near the 25 pulleys *D* *E*. The cam *J* is so placed upon the cam-wheel *M* that the bifurcated end of the belt-shipper will be swung over and the belt shifted to the fast-running pulley *D* just as the cam-wheel *M* is about to raise and strip the 30 flat, and swung back over and the belt shifted to the slow-running pulley *E* just as the flat is replaced and the stripping mechanism begins to travel toward the next flat.

The operation of the stripping mechanism 35 may be thus described: When the cam-wheel *M* is moving the stripping mechanism from flat to flat the belt *L*, which drives it through the pulley *H* and gears *h*, *R*, and *r* in the usual manner, is held by the belt-shipper upon the 40 slow-running pulley *E*; but when the cam *M* is about to lift and strip the flat the cam *J* changes the belt-shipper so as to carry over the belt onto the fast-running pulley *D*. As soon as the belt comes upon that pulley sufficiently 45 so that it has a hold upon it, although a greater part may still be upon the pulley *E*, the belt will be driven with the surface speed of the pulley *D*, and the pulley *E* will be carried forward at the same speed as the pulley *D* until the belt 50 is upon the pulley *D*, when the pulley *E* will be again driven by the train of gears at its normal slower rate, the pinion *k* being driven rapidly by the internal teeth of pulley *E* while that pulley was acted upon by pulley *D* and the belt, and the pulley *E* being driven by the 55 pinion *k* as soon as the pawl *y* drops, and remains in the ratchet-notch of ratchet-hub *k'*.

The belt remains upon the fast-running pulley and drives the cam *M* through the pulley *H* and gears *h*, *R*, and *r* at a rapid rate while it 60 lifts, strips, and replaces the flats. As soon as it has completed this operation the cam *M*, through its attached cam *J* and belt-shipper, shifts the belt *L* back onto the pulley *E*. As the belt edge passes upon the pulley *E* that 65 pulley will be driven at the same speed as the other and will continue to be so driven until the belt passes entirely off from the pulley *D*, after which it will be rotated at the slower speed with which it is intended to move as the 70 stripping mechanism moves from one flat to another by means of the pulley *D* and intermediate train of gears. In this manner excessive wear, caused by slipping and consequent injury to the belt as it is changed from a pulley running at one speed to one running at another, is prevented, and the speed with which the stripping mechanism is driven is increased or diminished at the proper times without jar or shock to the machinery as the change is 75 made.

What I claim as new and of my invention is—

1. The combination, with the pulleys *D* and *E*, and mechanism for driving the same at different rates of speed relatively to each other, and permitting of the two being driven at the same speed, of the belt-shipper *K*, cams *M* and *J*, and mechanism intermediate of said pulleys *D* and *E* and cams *M* and *J*, substantially as 85 90 described.

2. The combination, with the driving-shaft *a* and two pulleys mounted thereon, one of which is fast and the other free to turn on said shaft, of a train of gearing provided with a ratchet 95 pinion and pawl intermediate of said pulleys, a belt-shipper and stripper-arm, and intermediate connecting and operating mechanism between said pulleys and belt-shipper and stripper-arm, substantially as described. 100

3. The combination of the cams *M* and *J*, gear *R*, pulley *H*, belt *L*, fast-running pulley *D*, and slow-running pulley *E*, and speed-changing mechanism between said pulleys, with the belt-shipper *K*, which is actuated by the 105 cam *J*, and which periodically changes the speed with which the cam *M* is driven by shifting the belt from one pulley to the other, substantially as described.

GEO. H. CHANDLER.
